UNITED STATES PATENT OFFICE.

CHARLES MILLS, OF NEWTON UPPER FALLS, MASSACHUSETTS, ASSIGNOR
TO WILLIS C. SWIFT, OF FITZWILLIAM, NEW HAMPSHIRE.

LATHE FOR TURNING AXLES.

No. 828,614.

Specification of Letters Patent.

Patented June 19, 1906.

Application filed May 16, 1903. Serial No. 157,203.

To all whom it may concern:

Be it known that I, CHARLES MILLS, a citizen of the United States, residing at Newton Upper Falls, in the county of Middlesex and State of Massachusetts, have invented a certain new and useful Improvement in Lathes for Turning Axles, of which the following is a full, clear, concise, and exact description, reference being had to the accompanying drawings, forming a part of this specification.

My invention relates to improvements in lathes particularly designed for turning axles or articles of a similar nature.

One of the objects of my invention is to provide a lathe in which the articles to be turned or shaped may be passed endwise into position, so as to facilitate the handling of such articles.

Another object of my invention is to produce a lathe which will have special features of construction which will add to its utility.

With these and other objects in view I have designed the device shown in the accompanying drawings, which illustrate one embodiment of my invention, the several views of said drawings being as follows:

Figure 1 is a side elevation of my improved lathe. Fig. 2 is an end view thereof. Fig. 3 is a side elevation of a modification of my invention, and Fig. 4 is an end view of said modification.

Throughout the drawings like reference characters designate similar and corresponding parts.

In said drawings is shown a bed 1, of any suitable form, mounted upon legs 2. Upon the top of the bed-plate is arranged a suitable support or bearing 3, which is preferably secured to the bed by bolts 4. In said support is journaled a cylinder or barrel 5, which is provided with a gear 6 for rotating the same. The opening through said barrel is of suitable shape to receive the article to be turned, and screws 7 are provided for clamping said article to rotate with said barrel.

Journaled in suitable supports 8, mounted upon the rear of the bed, is a driving-shaft 9, which carries pulleys 10 and 11 for driving said shaft. A back shaft 12 is journaled in the support 3 and carries a gear 13, which meshes with a pinion 14 upon the driving-shaft. Also mounted on said back shaft is a pinion 15, which meshes with the gear 6 upon the revoluble cylinder or barrel journaled in

the support 3. By this arrangement of gearing the revoluble barrel 5 is rotated from the driving-shaft. At each end of the bed is slidably mounted a tool-carriage 17, which is moved along the bed by the usual mechanism. Each tool-carriage is provided with a tool-support 20, which is adjustable by a hand-wheel 21. The tool for turning the article being shaped by the lathe, as shown in the drawings, is clamped in position on the support by a plate 23, which is bolted in position by bolts 24.

At each end of the lathe is preferably arranged a plurality of foot-stocks 25, which are preferably all formed integral on a single hub 26, which is journaled upon a mandrel 27, projecting from the end of the bed. The several foot-stocks at each end preferably extend radially from their hub, and openings or spaces are provided between said foot-stocks. The hub of the foot-stocks is kept in position on the mandrel preferably by a plate 28, which is secured to said mandrel by bolts 29. By rotating the several foot-stocks they may successively be brought opposite the center of the lathe, and suitable mechanism may be provided for locking any one of the foot-stocks in position opposite the center of the lathe. By "center of the lathe" or "lathe center" I wish to be understood as meaning the rotary axis of the work.

It will be understood that one or any number of foot-stocks may be pivoted out of alinement with the lathe center, as above described, or such foot-stock or foot-stocks may be arranged in any suitable manner to permit the same to be brought opposite the lathe center when operating upon the article to be turned and to be removed therefrom when not operating upon said article or when said article is to be removed from the lathe.

In Fig. 1 of the drawings there is shown in dotted lines an axle. It will be observed that the axle is passed through the barrel or cylinder at the center of the lathe and clutched therein by the screws 7. By bringing the space between any two of the foot-stocks opposite the center of the lathe the axle may be withdrawn endwise from the lathe, or if it be desired to place an axle in position a similar location of one of said spaces will permit the axle to be placed in the lathe endwise. In this way the necessity of placing the axle in the lathe laterally is obviated, and by pro-

viding each end of the lathe with foot-stocks of the character described the axles or other articles which it is desired to shape may be placed in the lathe endwise from one end and 5 withdrawn endwise from the opposite end. In this way the handling of the axles in shaping the same may be materially facilitated. The several foot-stocks preferably each have an adjustable spindle 30, which is provided 10 with a hand-wheel 31 for operating the same. The spindle of each of the foot-stocks (shown opposite the center of the lathe in Fig. 1) is provided with a center 32 for supporting the axle. The several foot-stocks at each end of 15 the lathe may be provided with a different tool for performing various operations in shaping the axle. The foot-stock at the lower right-hand corner of Fig. 1 is shown as provided with a drill, and the foot-stock at 20 the lower left-hand corner of Fig. 1 is shown as carrying a tool for shaping the end of the axle. Any number of foot-stocks may be employed and as many tools carried thereby as may be deemed desirable, and each of said 25 foot-stocks may be brought opposite the center of the lathe and the tool carried thereby operated to perform its function. The several tools, such as the shaper or the drill, may be rotated from the back shaft by gearing or 30 other suitable means when they are in position to operate upon the axle, or the axle itself may be rotated and the tool remain stationary.

In the operation of the device shown in 35 Figs. 1 and 2 of the drawings the foot-stocks at one end of the lathe are rotated to bring the space between two of said foot-stocks opposite the center of the lathe, and then the axle is passed between said foot-stocks into 40 position on the lathe and clamped to the barrel or cylinder at the center of the lathe by screws 7. Then said barrel is operated to revolve the axle, and while the axle is revolving the shaper carried by one of the foot- 45 stocks is brought opposite the center of the lathe by revolving the foot-stock on which it is carried. Said shaper is now brought in contact with the end of the axle and turns the end thereof into the desired form. Next, 50 the drill carried by one of the foot-stocks is brought opposite the center of the lathe and a hole drilled for the insertion of the center carried by either one of the foot-stocks. After this hole has been made the tool is re- 55 moved and the foot-stock carrying the center is brought into the position and the center inserted in said hole. These operations are performed at each end, and when the centers are inserted in their respective holes at the 60 opposite ends of the axle the tools supported by the tool-carriages are moved into position to turn the periphery of the axle into the desired shape. Any number of foot-stocks may be provided and any tools which are 65 suitable to accomplish the desired purpose

may be employed, and, furthermore, the operation of said tools may be effected in any manner which may be deemed desirable. As above stated, suitable locking mechanism may be provided for fastening any one of the 70 stocks in position opposite the center of the lathe.

In Figs. 3 and 4 I have shown a modification of my invention. In said modification is shown a bed 33, supported on legs 34, as the 75 preferred form of my invention, and upon the top of said bed is secured a support 35, in which is journaled a barrel 36, having bolts 37 for clamping the article to be turned to said barrel. This barrel is provided with a 80 gear 38, with which meshes a gear 39. The gear 39 is mounted upon a back shaft 40, which is suitably journaled in the support 35 and in brackets 41, secured to the base. This back shaft 40 also has mounted thereon 85 pulleys 42 for turning the same. At each end of the bed is arranged a bearing box or support 43, in which is revolvably mounted a cylinder or barrel 44. This barrel or cylinder is provided with an opening 45, which may be 90 brought opposite the center of the lathe to permit the articles to be passed endwise into position on the lathe. Said barrel also carries a plurality of spindles 46, one of which is shown as provided with a drill 47 and the 95 other with a center 48. Each spindle is adjustable in the barrel, and a hand-wheel 49 is associated with each of said spindles for operating the same. Each of said spindles is disposed at a position on said barrel which permits the same to be brought opposite the center of the lathe when the barrel is rotated, and a hand-wheel 50, provided with a screw 52, adapted to engage the periphery of said barrel and threaded in the bearing-box 43, is 100 provided for locking said barrel in any desired position, so that when the several tools are brought opposite the center and are in use they may be firmly held in place.

A train of gears 53 is illustrated in the 105 modification of my invention for imparting rotary movement to the drill, and said train of gears is operated from a gear 54, mounted upon the back shaft. In this construction, as in the construction shown in the preferred 110 embodiment of my invention, the axle or other article to be turned may be passed endwise into position and also removed endwise from the lathe by bringing the hole 45 in the barrel or cylinder opposite the center of the 115 lathe. By having barrels of like construction at each end of the lathe the axle may be passed endwise into position and then shaped and finally removed endwise through the hole in the barrel at the opposite end of the 120 lathe. After an axle has been placed in position on the lathe in this construction of my device the same may remain in a stationary 125 position and the drill brought opposite the same and rotated to make the hole for the 130

center, and after said hole has been formed the drill is removed and the center brought into position.

Certain gears of the train for operating the drill are arranged to be separated, except when the tool is in position, and therefore said drill is only rotated when it is opposite the center of the lathe. As in my other construction, any number of spindles may be employed and any form of tools may be utilized.

Many changes may be made in the details of construction herein shown and described without in any way departing from the spirit of my invention.

Having described my invention, what I claim as new, and desire to secure by Letters Patent, is—

1. The combination with a lathe-bed, of a foot-stock at each end of said bed pivoted out of alinement with the lathe center and a chuck disposed between said foot-stocks for holding the article to be turned, said foot-stocks having movement transversely in a plane perpendicular to the lathe center, whereby the article to be turned may be easily inserted into said chuck at one end of the lathe and easily removed therefrom at the other end of the lathe, substantially as described.

2. The combination with a lathe-bed, of a plurality of foot-stocks arranged at each end of said bed, a central chuck mounted upon said bed for holding the article to be turned, said foot-stocks being pivoted out of alinement with the lathe center and having movement transversely in a plane perpendicular to the lathe center, whereby said foot-stocks may be brought successively opposite the lathe center and the article to be turned may be easily inserted into said chuck at either end of the lathe, substantially as described.

3. The combination with a lathe-bed, of a plurality of foot-stocks arranged at each end of said bed, means disposed between said foot-stocks for holding the article to be turned, said foot-stocks being pivoted out of alinement with the lathe center and having movement transversely in a plane perpendicular to the lathe center and means for locking any one of said foot-stocks when said foot-stock is opposite the lathe center, substantially as described.

4. The combination with a lathe-bed, of means carried by said bed for holding the article to be turned, a hub journaled at each end of said bed, and a plurality of foot-stocks carried by each of said hubs and movable transversely in a plane perpendicular to the lathe center, said foot-stocks being arranged with spaces between them, whereby the article to be turned may be passed endwise into position at one end of the lathe and removed endwise from position at the opposite end, substantially as described.

5. The combination with a lathe-bed, of a hub journaled at each end of said bed, a plurality of foot-stocks carried by each of said hubs and movable transversely in a plane perpendicular to the lathe center, a chuck disposed between said hubs for holding the article to be turned, and means for locking said hubs against rotation, substantially as described.

6. The combination with a lathe-bed, of a plurality of foot-stocks arranged at each end of said bed and movable transversely in a plane perpendicular to the lathe center, tools carried by said foot-stocks, and means for rotating the tool carried by one of said foot-stocks when said tool is in position to operate upon the article to be turned, substantially as described.

7. The combination with a lathe-bed, of a plurality of foot-stocks arranged at each end of said bed and movable transversely in a plane perpendicular to the lathe center, tools carried by said foot-stocks, and means for operating the tool carried by any one of said foot-stocks, substantially as described.

8. The combination with a lathe-bed, of means carried by said bed for holding the article to be turned, a plurality of foot-stocks arranged at each end of said bed, said foot-stocks being disposed out of alinement with the lathe center and movable transversely in a plane perpendicular to the lathe center, said foot-stocks being arranged with spaces between them, whereby the article to be turned may be inserted endwise into position at either end of the lathe, substantially as described.

9. The combination with a lathe-bed, of a hub journaled at each end of said bed, a plurality of foot-stocks carried by each of said hubs and having movement transversely in a plane perpendicular to the lathe center, said foot-stocks being arranged with spaces between them, a chuck mounted upon the bed for holding the article to be turned, means for rotating said chuck, and a tool-carriage on each side of said chuck, whereby the article to be turned may be passed endwise into position at one end of the lathe and removed endwise from position at the opposite end, substantially as described.

10. The combination with a lathe-bed, of a movably-mounted foot-stock arranged at each end of said bed, a chuck disposed between said foot-stocks for holding the article to be turned, said foot-stocks being movable in a plane perpendicular to the lathe center, whereby the article may be readily inserted into the chuck and removed therefrom at the end of the lathe.

11. The combination with a lathe-bed, of plurality of movably-mounted foot-stocks arranged at each end of said bed, a chuck disposed between the ends of said bed for holding the article to be turned, said foot-stocks

- being movable out of alinement with the lathe center in a plane perpendicular thereto, whereby articles may be readily inserted into said chuck at one end of the lathe and removed therefrom at the opposite end thereof.
12. The combination with a lathe-bed, of movably-mounted foot-stocks arranged at each end of the said bed, means disposed between said foot-stocks for holding the article to be turned, and a tool-holder mounted upon either side of said means, said foot-stocks being movable in a plane perpendicular to the lathe center and out of alinement therewith, whereby the article may be easily inserted into and removed from the holding means.
13. The combination with a lathe-bed, of a plurality of movably-mounted foot-stocks arranged upon each end of the said bed, a chuck disposed between said foot-stocks for holding the article to be turned, said foot-stocks being movable in a plane perpendicular to the lathe center, and means for locking any one of said foot-stocks in position when the same is in operative engagement with the article.
14. The combination with a lathe-bed, of a plurality of movably-mounted foot-stocks arranged at each end thereof carrying suitable tools, a chuck arranged between the ends of said bed for holding the article to be turned, said foot-stocks being movable in a plane perpendicular to the lathe center, and means for rotating the tool carried by any one of said foot-stocks when the same is in position to operate upon the article to be turned.
- In witness whereof I have hereunto subscribed my name in the presence of two witnesses.
- CHARLES MILLS.
